(57) **CLAIM**

The ornamental design for a wine cooling appliance, such as it has been referred to and shown on the drawings.

DESCRIPTION

FIG. 1 is a perspective view of a wine cooling appliance showing a new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines are for illustrative purposes only and form no part of the claimed design.
